UNITED STATES PATENT OFFICE.

JESSE H. HOLMES, OF ST. LOUIS, MISSOURI.

PRINTING-MACHINE.

SPECIFICATION forming part of Letters Patent No. 247,059, dated September 18, 1881.

Application filed July 11, 1881. (No model.)

To all whom it may concern:

Be it known that I, JESSE H. HOLMES, of St. Louis, Missouri, have made a new and useful Improvement in Printing-Machines, of which the following is a full, clear, and exact description, reference being had to the annexed drawings, making part of this specification, in which—

Figure 1 is a side elevation of a printing-press having the improvement; Fig. 2, a longitudinal vertical section, and Fig. 3 a transverse vertical section, of the improved press.

The same letters denote the same parts.

The present invention is an improvement in that class of cylinder printing-machines wherein an impression in different colors is obtained.

The special aim of the invention is to provide an improved means for obtaining an impression in two colors by means of a flat rather than a circular form, printing directly from the types.

It consists, mainly, in providing the cylinder with two impression-surfaces, which are spaced apart upon the cylinder a distance not less than the length of one of the surfaces, and employing, in combination therewith, a double or two-part bed, the bed having a reciprocating movement past the revolving cylinder, the parts of the bed and the forms being spaced apart a distance not less than the length of one of the impression-surfaces, the forms upon the two parts respectively of the bed being inked in different colors and the surfaces of the cylinder being presented successively to each part of the bed.

Referring to the drawings, A represents a printing-press, which, saving as modified by the present improvement, is substantially of the usual construction.

40 B represents the impression-cylinder. It is furnished with two impression-surfaces, C and D, arranged upon opposite sides of the cylinder, and each occupying not over one-fourth of the lateral surface of the cylinder. Each 45 of the depressions E and F therefore extends over at least one-fourth of the lateral surface of the cylinder. The latter rotates in the bearings b, in the direction indicated by the arrows, Figs. 1 and 2.

50 G H represent a two-part bed, that holds the form to be printed, the forms being inked in

different colors by their respective fountains, and being suitably relatively arranged to produce the desired impression. The cylinder rotates constantly in one direction. The bed G H 55 has a reciprocating movement beneath the cylinder, moving at the same rate as the cylinder.

The inking-fountains g and h are placed one on each side of the cylinder B, at a distance from the point R not less than the length of one 60 of the parts G H, so that each fountain-roller comes in contact with its form only.

The action of the construction is as follows: Suppose the bed G H is moving from right to left, as seen in Fig. 1, the impression-surface 65 C is just about to pass over the form on the part G of the bed and to take an impression—say its second, and in red—from that form. The bed moves to the left and the printed sheet is discharged from the cylinder at the point b'. 70 A fresh sheet is fed onto the impression-surface D at the point K, and takes its first impression—say in blue—from the form on the part H. After this last-named impression has been taken the bed moves back, as indicated 75 by the arrows in Fig. 2, from left to right, to its original position, the part H in this backward movement being presented to the depression E, the space between the parts G and H (or the forms respectively upon the parts G 80 and H) to the impression-surface C, and the part G to the depression F. As the bed starts again to the left the impression-surface D will be presented to the form on the part G, and in so doing the sheet will take its second impression in red, and is then ready to be discharged 85 from the cylinder at b', having passed over both forms and the printing having been completed. Meanwhile a new sheet has been taken on the surface C and the operation is repeated— 90 that is, at every one and one-half revolution of the cylinder B a sheet is printed in two colors.

By means of suitable appliances (not shown, as their construction is familiar) the customary 95 grippers will be worked to close at the point K each time the bed part G commences to pass under the cylinder toward the left, and the grippers will open at the point b' to discharge a sheet each time the part G of the bed leaves 100 the cylinder, passing to the left, and the surfaces C and D are presented alternately at the

points K and b' to receive and discharge the sheets.

In operating the above-described mechanism it is necessary to provide for keeping the impression-surfaces of the cylinder from contact with the forms on the parts G H during the movement of the bed from left to right, and also in the forward movement of the bed, saving as above described. This is effected by 10 spacing the surfaces G H apart a distance not less than the length of one of the surfaces C D, and so as to leave a depression between them, and fastening them rigidly to a base, g', which is moved reciprocatingly beneath the cylinder, 15 (or, what is equivalent thereto, by spacing the forms apart a distance not less than the length of one of the surfaces C D upon a plane single bed,) the bed being furnished with the rack L, and being moved to and fro, as described, by 20 means of mechanism similar to that in use in printing-presses for moving the bed, the gear M upon the shaft m, and turning with the gear N, driving the pinion O, which is attached to the shaft o, upon the inner end of which shaft 25 is the pinion P, which engages with and moves the rack L and bed G H.

I hereby disclaim the subject-matter of my pending application for Letters Patent for an

improvement in printing-presses, the serial number of which is 18,874.

30

I claim—

1. In a printing-machine, an impression-cylinder having two impression-surfaces arranged directly opposite each other upon the cylinder, and spaced apart thereon a distance not less than the length of one of the surfaces, in combination with a double or two-part flat bed, the two parts of the bed being spaced apart a distance not less than the length of one of the cylinder impression-surfaces, and the bed having 40 a reciprocating movement past the cylinder, for the purpose described.

2. In a printing-machine, the impression-cylinder B, having the two impression-surfaces C and D and the depressions E and F, arranged, 45 extended, and spaced apart, as described, in combination with the two-part bed G H, having the parts G and H made flat and rigidly attached to a single flat base, g', and spaced apart thereon, as described, and operating as 50 and for the purpose set forth.

JESSE H. HOLMES.
